SCREEN GRID CIRCUIT

Walter Van B. Roberts, Princeton, N. J., assignor
to Radio Corporation of America, a corporation
of Delaware

Application February 5, 1930, Serial No. 425,946

7 Claims. (Cl. 179—171)

My present invention relates to amplifier circuits, and more particularly to tuned radio frequency amplifier circuits employing electron discharge devices of the screen grid type.

As is well known to those skilled in the art, the screen grid tube was devised to reduce, to a considerable extent, the undesired coupling effect between the control electrode and anode of the usual triode. Such a screen grid device, or tetrode, usually has its screen element connected to an invariable source of positive potential to prevent the electric field of the anode from affecting the control electrode.

When a screen grid tube is employed in a stage of tuned radio frequency amplification, it is customary to shield the tuned input and output circuits from each other so that coupling, due to stray capacities, is prevented. However it has been found that an imperfection in the shielding of the tuned circuits results in sufficient undesired coupling to affect the amplifying power of the stage. An extremely small residual capacity of the order of one micro-micro-farad or less, easily produced by a slight imperfection in the shielding device, is found to reduce the stability of operation of the screen grid stage.

Now, I have devised a method of, and arranged means for, achieving the last step required to make the stability of screen grid stages perfect. That is to say, by my present invention it is possible to completely eliminate the bad effects of interstage capacity coupling, whereby the operating equivalent of one hundred per cent shielding is secured.

Accordingly, one of the main objects of my present invention is to provide a method of, and means for, completely stabilizing a tuned radio frequency amplifier employing a screen grid tube, which consists in employing in the input and/or output circuits of the amplifier a means for offsetting the tendency to oscillate arising by virtue of the interstage capacity coupling remaining after the input and output circuits have been imperfectly shielded from each other.

Another important object of the invention is to provide a method of, and means for, perfectly stabilizing a tuned radio frequency amplifier utilizing a tube of the screen grid type, which methods consist in employing, in the input and/or output circuits of the tetrode, arrangements for neutralizing the residual interstage capacity coupling remaining after the input and output circuits have been more or less perfectly shielded from one another, which arrangements comprise means for feeding back energy to the input cir-

cuit in degenerative phase to completely eliminate oscillations produced by the aforementioned residual capacity coupling.

Still other objects of the invention are to improve generally the efficiency of amplifiers employing screen grid tubes, and particularly tuned radio frequency amplifiers employing imperfect shielding for the input and output circuits, and to provide arrangements in such an amplifier for overcoming the effects of residual interstage capacity coupling produced by the imperfections in shielding, and which arrangements are not only reliable in operation but easily and economically applied to the amplifier.

The novel features which I believe to be characteristic of my invention are set forth in particularity in the appended claims, the invention itself, however, as to both its organization and method of operation will best be understood by reference to the following description taken in connection with the drawing in which I have indicated diagrammatically several circuit organizations whereby my invention may be carried into effect.

In the drawing,

Fig. 1 shows a stage of tuned radio frequency amplification employing a screen grid tube, and embodying a form of the invention.

Fig. 2 is a circuit similar to Fig. 1, and embodying a modified arrangement.

Fig. 3 is a circuit similar to Fig. 1, and embodying the preferred form of the invention.

Referring now to the accompanying drawing in which like characters of reference indicate the same parts in the different figures, Fig. 1 shows a stage of tuned radio frequency amplification employing a screen grid tube. The incoming signal energy is applied through a transformer coupling 1 to the tuned input circuit 2 of the tube 3. The cathode of the tube is shown, for the sake of simplicity, heated by a direct current source A, it being understood that a source of alternating current could also be used for the same purpose. The anode of the tube is connected to the positive terminal of a source B, through the primary 4 of the output transformer, the secondary of the said transformer being connected in the tuned input circuit of the succeeding stage.

The latter is connected to any well-known type of utilizing means, such as a detector, subsequent audio-frequency amplifiers and loud-speaker, the latter not being shown in order to preserve simplicity of disclosure and confine the description only to the subject matter of the invention. The screen grid element 5, is disposed between the anode and control electrode, and is also disposed

outside the anode to make its action more complete. The screen grid element is normally connected to a suitable point on the source B by a lead 6, and because of this connection its potential 5 with respect to ground cannot appreciably vary, thus preventing the electric field of the anode "reaching through" and affecting the control electrode.

In usual practice the input circuit of the tube 3 10 is confined within a shielding device 7, such as a metallic can, and the output circuit of the tube is likewise confined within a similar shielding device 8. However, due to various imperfections in the influence of the shielding devices, and also due to 15 coupling between the lead wires to the electrodes within the tube 3, a residual interstage capacity coupling 9 is found to exist between the input and output circuits of the stage. The shielding device and the interstage capacity coupling are shown 20 in dotted lines in Fig. 1.

One effective method of eliminating the effect 25 of the residual interstage coupling 9, which coupling tends to give rise to oscillations thus impairing the efficiency of the stage, is to insert a high resistance R in the control electrode connection 30 of the tube. The high frequency oscillations referred to flow through such a resistance, and the amount of coupling offered by the capacity 9 is not sufficient to sustain oscillations through such a 35 high resistance. Another effective method of overcoming the effect of the capacity 9 is to increase the resistance of the primary coil 4 in the anode circuit of the tube, as by making the primary of very fine wire of some high resistance 40 material. Since this coil 4 is practically never part of the tuned circuit, its resistance may be increased many times without interfering with normal tuning. Such arrangements may be 45 classed under the general term of "losser" arrangements, and it will be apparent to those skilled in the art that other similar arrangements 50 may be employed to overcome the effect of the residual interstage capacity coupling.

In Fig. 2 I have shown another arrangement for 55 overcoming the effect of the residual interstage capacity coupling 9. This arrangement consists in feeding back energy from the grid circuit of the tube 3 in degenerative phase to the output circuit. This is accomplished by inserting an additional 60 coil 10 in the input circuit of the tube, and coupling this coil to the secondary of the input transformer 1. Condenser C is connected between the end of the coil 10 and the anode of the tube 3. If the coil 10 is properly coupled to the input secondary, and 65 C is of suitable capacity, then the combination C—10 will produce on the anode a voltage just equal and opposite to that produced by the combination of the input secondary and the capacity 9. Therefore, the two effects will just neutralize 70 one another and no oscillations will occur.

Of course, exactly the same principle can be used in the reverse manner, that is by closely coupling the coil 10 to the output primary 4, and connecting the capacity C between the end of the coil 10 and the grid circuit, thus feeding back 75 energy in degenerative phase to the tuned input circuit of the tube. Still other combinations can be used, all operating on the same principle, viz., the residual interstage capacity coupling between the input and output circuit of the tube is offset, or neutralized by another coupling effect of equal magnitude and opposite phase. It will be found that such degenerative feed back arrangements overcome the oscillations produced by the resid-

ual capacity coupling 9 in such a manner that practically perfect shielding is secured.

A preferred arrangement that can be used to bring the shielding to perfection is shown in Fig. 3, wherein the stabilizing device is disposed directly in the screen grid circuit. In this arrangement a condenser C' of some few hundreds of micromicro-farads is connected in series in the lead 6 to the screen grid 5, this condenser being shunted by a choke coil L to carry direct current. The capacity reactance in the screen circuit multiplied by the radio frequency current passing through it gives a voltage on the screen which feeds back energy through the screen-to-control-grid capacity 11, shown in dotted lines in Fig. 3, in degenerative phase to the input tuned circuit, thus stabilizing the amplifier. In other words, it will be noted that in this arrangement the screen grid element possesses a varying potential created by the incoming signal energy itself, this being a feature distinct from that known in the prior art wherein it is necessary for the screen element to possess an invariable positive potential at all times.

All of the arrangements heretofore described have not been completely satisfactory when used in circuits where there was capacity coupling between the input and output circuits of the order of ten micromicro-farads but any of these arrangements can be easily and effectively applied, with satisfactory results, to the elimination of the effects of an extremely small residual interstage capacity coupling of the order of one micromicro-farad or less, such as results from imperfect shielding in connection with screen grid tubes. It will, thus, be apparent that it would be a desirable practice to use shielding between the input and output circuits of each amplifier stage to the extent that it is cheap and easy (as by stamping out stock metallic cans or by employing metallic cylinders having ends open) and to complete the stability of the amplifier by using arrangements as heretofore described.

It will be seen that by means of the arrangements before mentioned a method has been devised for overcoming the effects of residual interstage capacity coupling produced in an imperfectly shielded amplifier employing screen grid tubes. While I have indicated and described several systems for carrying my invention into effect, it will be apparent to one skilled in the art that my invention is by no means limited to the particular organizations shown and described, but that many modifications in the circuit arrangements, as well as in the apparatus employed, may be made without departing from the scope of my invention as set forth in the appended claims.

What I claim is:

1. In combination, a tetrode, including a screen grid element and a control electrode, a tuned input circuit associated with said control electrode, an output circuit including a direct current voltage source to which is connected the screen grid element, means for imperfectly shielding the input and output circuits from each other, and additional means eliminating the effect of the residual interstage capacity coupling of the imperfectly shielded circuits.

2. In combination, a tetrode including a screen grid element and a control electrode, a tuned input circuit associated with said control electrode, an output circuit including a direct current voltage source to which are connected the anode and screen grid element of said tetrode, means for imperfectly shielding the input and output circuits

from each other, and additional means including a capacitative path between the output and the input circuits for feeding energy in degenerative phase to the energy flowing through the residual 5 interstage capacity coupling of the imperfectly shielded circuits.

3. In combination, a tetrode including a screen grid element and a control electrode, a tuned input circuit associated with said control electrode, 10 an output circuit, said screen grid element being connected to a fixed direct current voltage point in said output circuit, means for imperfectly shielding the input and output circuits from each other, and additional means associated with the 15 screen grid element and the output circuit for producing a voltage on the screen which feeds back energy through the screen to control grid capacity in degenerative phase to the energy flowing through the residual interstage capacity coupling 20 between the imperfectly shielded circuits.

4. In combination, a tetrode including a screen grid element and a control electrode, a tuned input circuit associated with said control electrode, 25 an output circuit including a direct current voltage source to which is connected the screen grid element, means for imperfectly shielding the input and output circuits from each other, and additional means, including a capacitive reactance 30 in the screen grid circuit, for utilizing the radio frequency current for producing a voltage on the screen which feeds back energy through the screen to control grid capacity in degenerative phase to the input tuned circuit.

5. In combination in a tuned radio frequency 35 amplifier stage employing an electron discharge device including a screen grid element, a tuned input circuit associated with the control electrode and cathode of said tube and an output circuit associated with the screen grid and anode of said device, means for imperfectly shielding the input

and output circuits from each other, said output circuit including means for applying a constant positive bias to the screen grid when energy to be amplified is not flowing through the amplifier, 5 capacitative means, in the screen grid circuit, for utilizing radio frequency energy to be amplified for producing a varying voltage on the screen, and a choke coil in shunt with the capacitative means.

6. In combination, with a source of incoming 10 signals, an electron discharge tube including at least a cathode, a signal grid, an anode and a screen grid electrode surrounding said anode, an input circuit tuned to an incoming signal connected between the signal grid and cathode of said 15 tube, said tuned input circuit being coupled to said signal source, an output network connected between the cathode and said anode of the tube, said output network including a direct current voltage source, means for connecting said screen 20 grid electrode to a point on said voltage source, means for imperfectly shielding the tuned input circuit and said output network from each other, and additional means, including a resistor in the signal grid circuit of said tube, for eliminating 25 the effect of the residual interstage capacity coupling of the imperfectly shielded circuits.

7. An amplifier comprising a space discharge tube provided with a cathode, a control grid, an anode and a screen grid, an output circuit associated with the cathode and anode, an input circuit associated with the control grid and cathode, a source of positive potential for said screen grid, a condenser of low impedance to radio frequency currents in series between said source and 35 the screen grid, and a path having a high impedance to such currents between said source and screen grid, said second path comprising an inductance coil in shunt with the condenser.
